A. E. ANDERSON

AUTOMATIC RECLOSE CIRCUIT BREAKER SYSTEM

Original Filed June 5, 1922

UNITED STATES PATENT OFFICE.

ARVID E. ANDERSON, OF SCHENECTADY, NEW YORK, ASSIGNOR TO GENERAL ELECTRIC COMPANY, A CORPORATION OF NEW YORK.

AUTOMATIC RECLOSES-CIRCUIT-BREAKER SYSTEM.

Application filed June 5, 1922, Serial No. 566,001. Renewed May 7, 1925.

My invention relates to automatic reclosing circuit breaker systems and particularly to such systems in which a circuit breaker is arranged to connect automatically a source 5 of current to a load circuit, which may or may not be supplied with current at more than one point, as soon as the conditions on the load circuit are such that the circuit breaker can be closed without overloading 10 the source to be connected and the object of my invention is to provide a new and improved arrangement for accomplishing this result.

In accordance with my invention I provide an arrangement whereby the circuit breaker is closed in response to a predetermined voltage across the load circuit, when the load circuit is not supplied with current at some other point, and in response to the 20 current, which is proportional to the voltage difference, supplied to the load circuit from the source of current to be connected thereto by the closing of the circuit breaker when the load circuit is supplied with current at 25 some other point.

My invention will be better understood from the following description taken in connection with the accompanying drawing, and its scope will be pointed out in the appended claims.

Referring to the drawing which shows one embodiment of my invention, a load circuit 1, 2 is arranged to be supplied from two feeder circuits 3, 4 and 5, 6 which are connected to the sources of current 7 and 8, respectively. It is obvious, however, that both feeder circuits could be connected to the same source if it were so desired. The feeder conductor 5 is arranged to be connected to the load conductor 2 by any suitable means such as a circuit breaker 9 which may be closed either automatically or manually. The feeder conductor 4 is arranged to be connected to the load conductor 2 by means of the automatic reclosing circuit breaker 10. The circuit breaker may be of any suitable type. The feeder conductors 3 and 6 are permanently connected to the load conductor 1.

The circuit breaker 10 shown in the drawing comprises a closing coil 11 which, when energized, maintains the circuit breaker in its closed position. When the circuit breaker is closed and the load conditions are normal

the closing coil 11 is connected across the 55 feeder circuit 3, 4 by means of the contacts 12 of the overload relay 13, auxiliary contacts 14 of the circuit breaker and one set of contacts of the two-pole, single throw switch 15.

The overload relay 13 may be of any suitable type and as shown in the drawing is provided with a winding 17 which is connected in series with the conductor 4 and is so arranged that the relay opens its contacts 65 12 when the current supplied from the source 7 to the load circuit 1, 2 exceeds a predetermined value.

The other set of contacts of the two-pole, single throw switch 15, when closed, connects a current limiting means, such as a resistor 18, across the terminals of the circuit breaker 10 so that when the circuit breaker is open the resistor is connected in series with the conductors 2 and 4. The 75 coils of the relays 19 and 20 are connected to points on the resistor 18 so that the relays are controlled by the current supplied to the load circuit when the circuit breaker 10 is open. The relay 19 is so designed that it 80 opens its contacts and maintains them open as long as the voltage drop across the resistor 18 is above a predetermined value. The relay 20 is designed so that it does not close its contacts until the voltage drop 85 across the resistor 18 is above a predetermined value. The voltage drop required to close the contacts of the relay 20 is greater than the voltage drop which operate the relay 19.

The relay 19 controls one energizing circuit for the closing coil 11 of the circuit breaker when the circuit breaker is open. The relay 20 controls another energizing circuit for the closing coil 11 which also 95 includes the contacts 22 and 23 of the reclosing relay 24. These energizing circuits will be hereinafter described in detail. In order to prevent these energizing circuits for the closing coil 11 from being closed 100 until a predetermined time after the circuit breaker opens, these circuits include the contacts 25 of a time relay 26. The circuit for the coil of this time relay 26 is arranged to be connected across the feeder conductors 105 3, 4 by means of the auxiliary contacts 27 of the circuit breaker when it is open. This relay may be of any suitable construction so

that it does not close its contacts 25 until after the circuit breaker has been open predetermined time.

As shown in the drawing, the reclosing 5 relay 24 is a polarized relay comprising an armature 30 pivotally mounted within a winding 31 connected across the load circuit 1, 2 and between the pairs of polar projections 32, 32' and 33, 33' having opposite 10 polarities. The armature 30 carries the contact 22 which engages the stationary contact 23 when the relay is in its reclosing position. A restraining means such as a spring 39 tends to maintain the contact 22 15 out of engagement with the contact 23. The magnetic structure 34 of the relay may be either permanently magnetized or magnetized by a winding 35 which is energized from any suitable source such as the feeder 20 circuit 3, 4. The magnetic structure 34 is magnetized so that the polar projections 32 and 33 are of opposite polarity and are of the same polarity as the ends 37 and 38, respectively, of the armature 30. With 25 such an arrangement, it is apparent that when the contacts 22 and 23 are open the armature 30 tends to move on its pivot in a direction to close its contacts. By adjusting the spring 39 the relay can be made so that 30 it closes its contacts 22 and 23 when the voltage impressed upon the operating winding 31 is above a predetermined value. The resistance of the operating winding 31 is 35 high so that an excessive current does not flow through it when the circuit breaker is closed and full voltage is impressed upon the load circuit.

The operation of the arrangement shown 40 in the drawing is as follows: When the switch 15 and the circuit breaker 10 are closed and the operating conditions are normal so that the contacts 12 of the overload relay 13 are closed the circuit breaker is held in its closed position by the energization 45 of the closing coil 11, the holding circuit of which is as follows: from the feeder conductor 3 through the closing coil 11, closed contacts 12 of the overload relay 13, closed auxiliary contacts 14 of the circuit breaker, closed contacts of the switch 15 to the feeder conductor 4. Since the circuit breaker in its closed position short circuits the resistor 18, the contacts of 50 the relay 19 are closed and the contacts of the relay 20 are opened. The circuit for the closing coil 11 through the contacts of the relay 19 is open, however, at the contacts 25 of the time relay 26 since the circuit of the coil of the time relay is open 55 at the open auxiliary contacts 27 of the circuit breaker. The contacts 22 and 23 of the reclosing relay 24 are closed since full potential is impressed on the winding 31 which is connected across the load circuit 1, 60 2 and full potential is impressed on the

magnetizing winding 35 which is connected across the supply circuit 3, 4 by means of the contacts 22 and 23, auxiliary contacts 14 and contacts of the switch 15.

In case of an overload or short circuit on 70 the load circuit 1, 2, the overload relay 13 operates and opens its contacts 12. The opening of these contacts opens the normally closed circuit of the closing coil 11 of the circuit breaker 10 so that the circuit 75 breaker opens. The opening of the circuit breaker opens its contacts 14 so that the magnetizing winding 35 of the reclosing relay is deenergized and this relay opens its contacts 22 and 23. The opening of the circuit breaker also closes its auxiliary contacts 27 thereby connecting the coil of the time relay 26 across the feeder circuit 3, 4. The purpose of this relay is to allow the 80 circuit conditions to become stabilized. The plunger of this relay begins to rise and 85 after a certain time the contacts 25 of this relay are closed. The opening of the circuit breaker 10 also opens the short circuit around the current limiting resistor 18. 90 This resistor is so designed that it limits the current supplied to the load circuit to a very small value and therefore the overload relay 12 closes its contacts after the circuit breaker opens. The small current flowing 95 through the current limiting resistor 18 produces a voltage drop across the resistor 18 which is an indication of the load conditions. This voltage drop which varies with the current supplied to the load circuit is used to 100 control the reclosing of the circuit breaker when the circuit breaker is open.

It is evident that if the load circuit 1, 2 is not supplied with current from some other source the voltage drop across the resistor 105 18 is a direct indication of the resistance of the load circuit, whereas if the load circuit 1, 2 is supplied from some other source the voltage drop across the resistor 18 does not depend solely on the load resistance but has 110 a value depending on the number of other sources and distance between the short circuit or overload and the other sources supplying current to the load circuit and the magnitude of the overload or short circuit. 115 Since the resistance of the current limiting resistor 18 is much greater than the normal full load resistance, it is evident that for a given load resistance the voltage drop across the current limiting resistor 18 120 is very much greater when the load circuit is not supplied from some other source than when it is supplied from one or more other sources. Therefore, it is evident that when the circuit breaker is open the voltage drop across the resistor 18 is an indication of whether or not the load circuit is supplied 125 with current from some other source.

Let it be assumed that when the circuit breaker 10 opens in response to an overload 130

or short circuit, the load circuit 1, 2 is not supplied with current from some other source. Under these conditions the circuit breaker 9 is open and the voltage drop across the current limiting resistor 18 is substantially equal to the voltage of the feeder circuit 3, 4. Since the relay 19 is preferably arranged to open and close its contacts in response to very small voltage drops across the resistor 18 and the relay 20 is preferably arranged to close its contact when the voltage drop across the resistor 18 is above a predetermined value, usually some value between 60 and 95 per cent of the normal voltage of the feeder 3, 4, the contacts of the relay 19 are opened and the contacts of the relay 20 are closed when the circuit breaker opens. The closing of the contacts of the relay 20 connects the magnetizing winding of the reclosing relay 24 across the feeder circuit 3, 4. As heretofore set forth, the operating winding 31 is connected across the load circuit 1, 2. When the load resistance increases to a predetermined value the voltage impressed upon the operating winding 31 increases to a value sufficient to close the contacts 22 and 23. When these contacts close, an energizing circuit is completed for the closing coil 11 of the circuit breaker 10 to close the circuit breaker. This circuit is as follows: from the feeder conductor 3 through the closing coil 11 of the circuit breaker, closed contacts 12 of the overload relay 13, contacts 22 and 23 of the reclosing relay 24, contacts of the relay 20, contacts 25 of the time relay 26, contacts of switch 15 to the feeder conductor 4. When the circuit breaker closes it opens its contacts 27 thereby deenergizing the coil of the time relay 26 and closes its contacts 14, thereby completing the holding circuits heretofore traced for the magnetizing coil 35 and for the coil 11 so that the circuit breaker is held in its closed position. Since the closing of the circuit breaker 10 short circuits the resistor 18 the coils of the relays 19 and 20 are deenergized. Let it now be assumed that when the circuit breaker opens, the load circuit 1, 2 is supplied with current from some other source, such, for example, as the source 8. Under these conditions the voltage drop across the current limiting resistor 18 which is equal to the difference between the voltage across the feeder circuit 3, 4 and the load circuit 1, 2 is not great enough to cause the relay 20 to close its contacts. If, however, the short circuit or overload remains connected to the load circuit the voltage drop across the current limiting resistor is sufficient to cause the relay 19 to open its contacts before the time relay 26 closes its contacts 25. Preferably the relay 19 is designed so that its pick-up and drop-out values are as near the same value as possible. So long as the voltage difference between the feeder circuit 3, 4 and the load circuit 1, 2 is above a predetermined value the relay 19 maintains its contacts open. When the voltage difference decreases below the predetermined value, the contacts of the relay 19 close thereby completing an energizing circuit for the closing coil 11 of the circuit breaker. This circuit is as follows: from the feeder conductor 3 through the closing coil 11, contacts 12 of the overload relay 13, contacts of the relay 19, contacts 25 of the time relay 26, contacts of the switch 15 to the feeder conductor 4. When the circuit breaker 10 closes the resistor 18 is short circuited and the apparatus is restored to its normal condition in the manner heretofore described.

In case the load is entirely disconnected from the load circuit when it is not supplied from some other source and the circuit breaker 10 is open the only current through the resistor 18 is that which flows through the magnetizing winding 35 and since the resistance of this winding is great the voltage drop across the resistor is very small. Consequently, the contacts of the relay 19 are closed and the contacts of the relay 20 are open so that when the time relay 26 closes its contacts 25 after the circuit breaker has been open a predetermined time, the heretofore described energizing circuit for the closing coil 11 of the circuit breaker 10 through contacts of the relay 19 is completed to effect the closing of the circuit breaker in the same manner as above described when the load circuit is supplied from some other source.

By opening the switch 15 the circuit of the closing coil is interrupted so that the circuit breaker 10 opens and the circuits of the reclosing relay 24 and time relay 26 are interrupted so that the reclosing equipment is rendered inoperative.

While I have shown and described only one embodiment of my invention I do not desire to be limited thereto but seek to cover in the appended claims all those modifications and changes that fall within the true spirit and scope of my invention.

What I claim as new and desire to secure by Letters Patent of the United States, is:—

1. In an automatic reclosing circuit breaker system, the combination with a load circuit adapted to be supplied with current at a plurality of points, a supply circuit arranged to be connected to said load circuit, a circuit breaker for controlling the connection between said supply circuit and said load circuit, means adapted to connect said load and supply circuits together when said circuit breaker is open, and closing means for said circuit breaker, of means operative in response to the voltage across the load circuit when the current supplied to said load circuit from said supply circuit is greater than a predetermined value

- when said circuit breaker is open to effect the operation of said closing means, and means operative in response to the current supplied to said load circuit from said supply circuit when said circuit breaker is open and said current is less than said first mentioned predetermined value to effect the operation of said closing means.
2. In an automatic reclosing circuit breaker system, the combination with a load circuit adapted to be supplied with current at a plurality of points, a supply circuit arranged to be connected to said load circuit, a circuit breaker for controlling the connection between said supply circuit and said load circuit, a current limiting device arranged to be connected in series between said supply and load circuits when the circuit breaker is open, and closing means for said circuit breaker, of means operative in response to a predetermined voltage across said load circuit when the current through said current limiting device exceeds a predetermined value to effect the operation of said closing means, and means operative in response to the current through said current limiting device when said current is less than said first mentioned predetermined value to effect the operation of said closing means.
3. In an automatic reclosing circuit breaker system, the combination with a load circuit adapted to be supplied with current at a plurality of points, a supply circuit arranged to be connected to said load circuit, a circuit breaker for controlling the connection between said load circuit and said supply circuit, and closing means for said circuit breaker, of means operative in response to the voltage across said load circuit when the voltage difference between said load circuit and said supply circuit exceeds a predetermined value to effect the operation of said closing means and means operative in response to a predetermined voltage difference between said load and supply circuits when said first mentioned voltage difference is less than said predetermined value to effect the operation of said closing means.
4. In an automatic reclosing circuit breaker system, the combination with a load circuit adapted to be supplied with current at a plurality of points, a supply circuit arranged to be connected to said load circuit, a circuit breaker for controlling the connection between said load circuit and said supply circuit, a current limiting device arranged to be connected in series with said load and supply circuits when said circuit breaker is open, and closing means for said circuit breaker, of means operative in response to a predetermined voltage across said load circuit when the voltage drop across said current limiting device exceeds a predetermined value to effect the operation of said closing means, and means operative in response to a predetermined voltage drop across said current limiting device when said first mentioned voltage drop across said current limiting device is less than said predetermined value to effect the operation of said closing means.
5. In an automatic reclosing circuit breaker system, the combination with a load circuit adapted to be supplied with current at a plurality of points, a supply circuit arranged to be connected to said load circuit, a circuit breaker for controlling the connection between said load circuit and said supply circuit, and closing means for said circuit breaker, of means operative in response to a predetermined voltage across said load circuit when the voltage difference between said load circuit and said supply circuit if said first mentioned voltage difference is less than said first mentioned value to effect the operation of said closing means, and means arranged to prevent said circuit breaker from closing before the elapse of a predetermined time after its opening.
6. In an automatic reclosing circuit breaker system, the combination with a load circuit adapted to be supplied with current at a plurality of points, a supply circuit arranged to be connected to said load circuit, a circuit breaker for controlling the connection between said load circuit and said supply circuit, a current limiting device arranged to be connected in series with said load and supply circuits when said circuit breaker is open, and closing means for said circuit breaker, of means operative in response to a predetermined voltage across said load circuit when the voltage drop across said current limiting device exceeds a predetermined value to effect the operation of said closing means, and means operative in response to a predetermined voltage drop across said current limiting device when said first mentioned voltage drop across said current limiting device is less than said predetermined value to effect the operation of said closing means.
7. In an automatic reclosing circuit breaker system, the combination with a load circuit adapted to be supplied with current at a plurality of points, a supply circuit arranged to be connected to said load circuit, a circuit breaker for controlling the connection between said supply circuit and said load circuit, and means for closing the circuit.

- cuit breaker, of means responsive to the current supplied to said load circuit from said supply circuit when said circuit breaker is open for controlling the closing of said circuit breaker, means responsive to the voltage across the load circuit for controlling the closing of said circuit breaker independently of said current responsive means, and means responsive to the current supplied to said load circuit from said supply circuit when the circuit breaker is open, to prevent the closing of the circuit breaker by said voltage responsive means when the current supplied to said load circuit is less than a predetermined value.
8. In an automatic reclosing circuit breaker system, the combination with a load circuit adapted to be supplied with current at a plurality of points, a supply circuit arranged to be connected to said load circuit, a circuit breaker for controlling the connection between said supply circuit and said load circuit, a current limiting device arranged to be connected in series between said supply and load circuits when said circuit breaker is open, means responsive to the voltage drop in said current limiting device for controlling the closing of said circuit breaker, means responsive to the voltage across the load circuit for controlling the closing of said circuit breaker independently of said voltage drop responsive means, and means responsive to the voltage drop in said current limiting device to prevent the closing of the circuit breaker by said means responsive to the voltage of the load circuit when the difference between the supply and load circuit voltages is less than a predetermined value.
- 40 9. In an automatic reclosing circuit breaker system, the combination with a load circuit adapted to be supplied with current at a plurality of points, a supply circuit arranged to be connected to said load circuit, a circuit breaker for controlling the connection between said load circuit and said supply circuit, and a closing coil adapted when energized to close said circuit breaker, of a relay operative in response to a predetermined voltage difference between said load and supply circuits to effect the energization of said closing coil, a second relay operative in response to a predetermined voltage across said load circuit to effect the energization of said closing coil, and a third relay operative in response to a predetermined voltage difference between said load and supply circuits to render said second relay inoperative to effect the energization of said closing coil.
- 50 10. In an automatic reclosing circuit breaker system, the combination with a load circuit adapted to be supplied with current at a plurality of points, a supply circuit arranged to be connected to said load circuit, a circuit breaker for controlling the connection between said load circuit and said supply circuit, and a closing coil adapted when energized to close said circuit breaker, of a relay operative in response to a predetermined voltage difference between said load and supply circuits to effect the energization of said closing coil, a second relay operative in response to a predetermined voltage across said load circuit to effect the energization of said closing coil, and a third relay operative in response to a predetermined voltage difference between said load and supply circuits to render said second relay inoperative to effect the energization of said closing coil, and a time relay operative in response to the opening of the circuit breaker and voltage resumption to prevent the energization of said closing coil until a predetermined time after said circuit breaker opens.
- 55 11. In an automatic reclosing circuit breaker system, the combination with a load circuit supplied with current at a plurality of points, a supply circuit adapted to be connected to said load circuit, a circuit breaker for controlling the connection between said load circuit and said supply circuit, an impedance adapted to be connected in series with said load and supply circuits when said circuit breaker is open, a closing coil for said circuit breaker, a holding circuit for said closing coil arranged to be completed when said circuit breaker is closed, and an overload relay arranged to interrupt said holding circuit when the current supplied from said supply circuit to said load circuit exceeds a predetermined value, of an energizing circuit for said closing coil, contacts in said energizing circuit, a relay operative in response to a predetermined voltage drop across said impedance to effect the closing of said contacts, a second energizing circuit for said closing coil, two sets of contacts in said second energizing circuit, a relay operative in response to a predetermined voltage drop across said load circuit to effect the closing of one of said last mentioned sets of contacts, a relay operative in response to a predetermined voltage drop across said impedance to effect the closing of the other one of said last mentioned sets of contacts, other contacts in both of said energizing circuits, a time relay adapted to close said other contacts, and a circuit for said time relay arranged to be completed by the opening of said circuit breaker.
- 60 12. In an automatic reclosing circuit breaker system, two electric circuits, a circuit breaker for connecting said circuits together, closing means for said circuit breaker, means responsive to the voltage across one of said circuits for effecting the operation of said closing means, means responsive to a predetermined difference between the voltage of said circuits for effect-

ing the operation of said closing means, and means controlled by an electric condition of one of said circuits for determining which of said voltage responsive means shall effect 5 the operation of said closing means.

13. In an automatic reclosing circuit breaker system, a supply circuit, a load circuit, a circuit breaker for connecting said circuits together, overload responsive means 10 for effecting the opening of said circuit breaker, means responsive to the voltage across said load circuit for effecting the reclosure of said circuit breaker, means responsive to a predetermined difference between the voltages of said circuits for effecting the reclosure of said circuit breaker, and means controlled by an electric condition of said load circuit when said circuit breaker 15 is open for selecting which of said voltage responsive relays shall effect the reclosure 20 of said circuit breaker.

14. In an automatic reclosing circuit breaker, a supply circuit, a load circuit, a circuit breaker for connecting said circuits together, overload responsive means for effecting the opening of said circuit breaker, current limiting means arranged to be connected between said circuits when said circuit breaker is open, means responsive to the voltage across said load circuit for effecting 25 the reclosure of said circuit breaker, means responsive to a predetermined voltage drop across said current limiting means for effecting the reclosure of said circuit breaker, and means controlled by an electric condition of 30 said load circuit when said circuit breaker is open for selecting which of said two last mentioned means shall effect the reclosure of said circuit breaker.

In witness whereof, I have hereunto set 40 my hand this first day of June, 1922.

ARVID E. ANDERSON.
